MOP STAND

Nellie M. Gage, Dayton, Ohio

Application March 24, 1945, Serial No. 584,642

3 Claims. (Cl. 248—119)

1

This invention relates to an apparatus upon which wet articles such as a mop can be placed to catch the drippage from the mop and thereby prevent the water from dropping on the floor.

An object of the invention is to provide a portable stand upon which a wet article such as a mop can be supported in a vertical position to drain the water from the article, and also to provide a means for collecting or catching the drip from the article.

Another object of the invention is to provide a portable mop stand that can be placed in any convenient location for a housewife, that is provided with a grill to support a wet mop and a collecting pan positioned beneath the grill for the purpose of catching the drip from the mop, and means is also provided for holding the handle of the mop in a vertical position.

Still another object of the invention is to provide a portable stand for receiving a wet mop in accordance with the foregoing object wherein the grill and the receiving pan for receiving the drip from the mop are constructed as an integral unit.

Further objects and advantages will become apparent from the drawings and the following description.

Figure 1 is a vertical cross-sectional view of a mop stand constructed in accordance with this invention.

Figure 2 is a vertical cross-sectional view taken substantially along line 2—2 of Figure 1.

Figure 3 is a perspective elevational view of a slightly modified shape of the mop stand illustrated in Figures 1 and 2.

Figure 4 is a perspective elevational view of a modified arrangement of the mop stand.

Figure 5 is a perspective elevational view of a still further modified form of the mop stand.

Figure 6 is a horizontal cross-sectional view taken substantially along line 6—6 of Figure 1.

This invention relates to a device that is adapted to support a mop after it has been used to receive the drippage from the mop when placed in its storage location, and yet provide for circulation of air around the mop to permit freedom of drying and avoid molding as a result of storing the mop on a flat, unventilated surface. When the housewife is finished with the use of a mop, the conventional thing for her to do is to set the mop in a corner until she is ready to use it the next time. If the mop is set directly on the floor, considerable damage is occasioned to the floor surface, whereas if the mop is placed in a pan of any kind, the complete drying of the mop

is retarded because air cannot circulate around the various strands of the mop, and drainage is not conducted away from the mop, so that under these conditions a slow drying of the mop can result in a molding of it.

In this invention, therefore, the mop stand is adapted to support a wet mop in a position that will permit drainage of water from the mop and will allow circulation of air around the entire mop and thereby promote rapid drying of the same. The mop stand as illustrated in Figures 1 and 2 consists of a shallow pan 10 having any suitable rust-resisting finish above which there is positioned a grill 11 that may consist of a plurality of individual wires 12 that extend transversely between the vertically positioned brackets 13. The wires 12 are secured to the brackets 13 as by means of a spot-welding operation, and the brackets 13 are in turn secured to the pan 10 by a similar spot-welding operation. The grill 11 permits complete freedom of movement of air above and below the grill and through the same.

A bracket member 14 is secured to the rear edge 15 of the pan 10, the bracket 14 having a vertical leg portion 16 and a horizontal arm 17 that terminates in a holder 18 that is adapted to receive the handle of a mop. The holder 18, as illustrated in Figure 6, consists of a bar 19 that is provided with a hook 20 on each end thereof, a space 21 being provided between the hooks 20 to allow insertion of a mop handle into either of the hooks 20.

The use of the mop stand is illustrated in Figures 1 and 2 wherein the mop 25 is positioned upon the grill 11 with the handle 26 resting in one of the hooks 20, thus holding the handle in a substantially vertical position that is out of the way. The two hooks 20 are provided for the purpose of use by a left or right-handed person, it being conventional for a right-handed person to lay the mop handle in the right-hand hook, as viewed in Figure 3, and a left-handed person to lay the handle of the mop in the left-hand hook, as viewed in Figure 1.

From the foregoing description, it will be apparent that with the mop located in position on the mop stand as illustrated in Figures 1 and 2, the water drainage from the mop will collect in the pan 10 and that room air is permitted freedom of circulation through and around the mop to permit rapid drying of the same. Also, since the mop does not rest upon a flat surface, molding of the mop is prevented.

In Figure 3 there is illustrated a slightly modified design of the mop stand illustrated in Figures

1 and 2 wherein the pan 10a is illustrated as being a circular pan that supports a circular grill 11a whereas the pan 10 and the grill 11 of Figures 1 and 2 have a substantially rectangular form.

In Figure 4 there is illustrated another modified arrangement of the construction of the mop stand wherein there is provided a rectangular shallow pan 30 that supports a wire grill 31 upon a pair of supporting brackets 32, the grill 31 being secured to the supporting brackets 32 which are in turn secured to the bottom wall of the pan 30.

The principal difference between the device illustrated in Figure 4 and that disclosed and described with regard to Figures 1 and 2 is in the support arm for holding the handle of the mop in a vertical position. In Figure 4 the support bracket for the mop handle consists of a pair of wires that are twisted together to form a vertical leg 33 and a horizontal leg 34. The wires comprising the bracket 35 are spread apart at the bottom in the form of a Y that are secured to a bracket member 36 that extends upwardly from the pan 30, the bracket 36 being secured to the member 35 and the pan 30 by suitable operations, such as a spot-welding operation.

The wires that comprise the bracket member 35 are at their ends formed into the hooks 37 and 38 that are spaced apart from one another so that a mop handle can be placed in either hook 37 or 38.

In Figure 5 there is illustrated another modified form of the mop stand wherein the stand consists of a rectangular angle-iron frame 50 that has legs 51 secured to each corner thereof. The upper ends of the legs 51 are secured to an open bottom pan 52 that has a grill-work 53 provided therein as the bottom portion of the pan 52. A vertical bracket 54 is secured to the angle-iron frame 50, and if desired, to the pan 52, and extends upwardly therefrom but is continuous with a horizontally extending arm 55 that terminates in the mop handle holder 56 having the hooks 57 and 58 to receive the mop handle.

A shallow, removable pan 59 is adapted to rest upon the angle-iron frame 50 in position beneath the grill 53 to catch the drip from a wet mop set upon the grill 53.

While the mop stand heretofore disclosed and described has been referred to as being positioned upon the floor, yet there are times when it is desirable to attach the mop stand to a wall, either while it is being supported upon the floor, to prevent removal of the mop stand from the premises, or to suspend the same from a wall.

For this purpose, the bracket 14, see Fig. 1, is provided with the perforations or holes 40 through which suitable fastening means may extend for attaching the mop stand to a wall or for supporting the mop stand from a wall, if desired. Similar holes or perforations 41 are provided in the bracket of the device illustrated in Figure 3, and like perforations 42 are provided in the bracket 54 of the device illustrated in Fig. 5.

In the device illustrated in Fig. 4, the bracket 36 is provided with the perforations 43 and the wires comprising the bracket 35 are split apart to provide an opening 44 to receive a fastening device.

While the apparatus has been described with reference to its use in connection with a washing mop, yet it will also be understood that it is usable with an oil mop, or any other wet article that may have liquid drip therefrom.

While the apparatus disclosed and described herein constitutes preferred forms of the invention, yet it will be understood that the device is capable of mechanical alteration without departing from the spirit of the invention, and that all modifications that fall within the scope of the appended claims are intended to be included herein.

Having thus fully described my invention, what I claim as new and desire to secure by Letters Patent is:

1. A mop stand that comprises a horizontal grill adapted to support a mop, a pan positioned beneath said grill, leg means on said grill supporting said grill upon said pan in spaced relation thereto, and a bracket arm extending upwardly from one side of said pan to a position above said grill and terminating in means for receiving the handle of a mop to support the same in a substantially vertical position when the mop rests upon the grill.
2. A mop stand that comprises a shallow pan, bracket means spaced from one another secured to said pan and extending upwardly therefrom, a grill secured to the upper ends of said bracket means for positioning the grill in spaced relationship to the bottom of said pan for supporting a mop thereon to allow drainage from the mop into the pan, and a bracket secured to said pan extending upwardly therefrom and terminating in means positioned above said grill and in spaced relationship thereto for receiving and holding the handle of a mop positioned on the grill in a substantially vertical position.
3. A mop stand that comprises a shallow pan, bracket means spaced from one another secured to said pan and extending upwardly therefrom, a grill secured to the upper ends of said bracket means for positioning the grill in spaced relationship to the bottom of said pan for supporting a mop thereon to allow drainage from the mop into the pan, and bracket means extending upwardly from said pan to support the handle of a mop in a substantially vertical position when the mop is placed upon said grill, said bracket means consisting of a vertical leg secured at the bottom edge thereof to said pan, a horizontal arm extending from said vertical leg and terminating in a pair of oppositely disposed hook means positioned in spaced relationship to allow a handle on a mop to be inserted therebetween for positioning in either of said hook means, said bracket and hook means being formed from a pair of twisted wires.
